(57) **CLAIM**

The ornamental design for a cat window perch, as shown and described.

DESCRIPTION

FIG. 1 is a front perspective view of a cat window perch, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front perspective view of the cat window perch of FIG. 1, shown in a second configuration with window mounts in an environment of use; and,

FIG. 10 is a front perspective view of the cat window perch of FIG. 1, shown in a third configuration attached to a window frame in an environment of use.

The broken lines showing of window mounts in FIG. 9 and a window frame in FIG. 10 depict environmental subject matter and forms no part of the claimed design. All remaining broken lines in FIGS. 1-10 depict portions of the cat window perch that form no part of the claimed design.

1 Claim, 10 Drawing Sheets
